[73] Assignee: Continental Plastic Containers, Inc., Norwalk, Conn.

[57] CLAIM

The ornamental design for an exterior surface of a sidewall for a juice container, as shown and described.

[**] Term: 14 Years

DESCRIPTION

[21] Appl. No.: 4,827

FIG. 1 is a top, front, right side isometric view of an exterior surface of a sidewall for a juice container showing the new design;

[22] Filed: Feb. 16, 1993

FIG. 2 is a rear elevational view thereof;

[52] U.S. Cl. D9/528

FIG. 3 is a front elevational view thereof;

[58] Field of Search D9/531, 528, 527, 535,
D9/536; 215/1 R, 1 C, 100 A

FIG. 4 is a top plan view thereof; and,

[56] References Cited

FIG. 5 is a right side elevational view thereof.

U.S. PATENT DOCUMENTS

The partially undisclosed left side forms a mirror image of the right side seen in FIG. 5. The neck shown at the top in broken lines is for illustrative purposes only and forms no part of the claimed design.
